UNITED STATES PATENT OFFICE.

ALBERT GREENEBAUM, OF PHILADELPHIA, PENNSYLVANIA.

SHIRT-WAIST.

1,044,881.

Specification of Letters Patent. Patented Nov. 19, 1912.

Application filed June 11, 1912. Serial No. 702,997.

To all whom it may concern:

Be it known that I, ALBERT GREENEBAUM, a citizen of the United States, residing in the city and county of Philadelphia, State 5 of Pennsylvania; have invented a new and useful Shirt-Waist, of which the following is a specification.

My invention consists of an improved adjusting device for the waistband of boys' 10 shirt-waists, whereby the drawing strings now in general use are dispensed with.

It further consists of other novel features of construction, all as will be hereinafter fully set forth.

15 The annexed drawings and the following description set forth in detail one mechanical form embodying the invention, such detail construction being but one of various mechanical forms in which the principle of the 20 invention may be used.

In said annexed drawings:—Figure 1 represents a perspective view of a boy's shirt-waist provided with my improvement. Fig. 2 represents a view of as much of such 25 shirt-waist as will illustrate one adjustment of the device. Fig. 3 represents a similar view illustrating another adjustment.

Similar numerals of reference indicate corresponding parts in the figures.

30 Referring to the drawings, the numeral 1 indicates a shirt-waist of the usual or of any desired or required construction and provided with the usual waistband, 2, fastened by a button, 3, and buttonhole, 4. On each 35 side and about above the hips, the waistband is provided with a button, 5, and at each side of each of said buttons and at a suitable distance from the same is secured a loop, 6, adapted to be buttoned over the button. The waist may be worn with the waistband loose, or one loop may be buttoned 40 over one of the buttons. If it is desired to further tighten the waist-band, a loop may be buttoned over the button on the other side, or 45 three loops may be buttoned over the but-

tons, or four loops may be buttoned, when the waist-band is tightened to its full extent. Each loop forms a fold in the waist-band, so that considerable adjustment of the girth of the waist-band is attained by my device. 50

The present device dispenses with the drawing-string heretofore employed in drawing the waist-band of a boy's shirt-waist around the waist, and which string has been liable to be pulled out and lost, to be broken 55 or to disappear in the casing, at the bottom of the waist, while it is being laundered. Five different girth-adjustments may be had with my device, having two buttons and four loops, and more adjustments may be had by 60 increasing the number of buttons and pairs of loops.

Other modes of applying the principle of my invention may be employed for the mode herein explained. Change may therefore be 65 made as regards the mechanism thus disclosed, provided the principles of construction set forth respectively, in the following claim are employed.

Having thus described my invention what 70 I claim as new and desire to secure by Letters Patent, is:—

In a shirt waist, a waistband; a single button secured upon each side of the same and a pair of loops for each button, and situated 75 on opposite sides thereof, each loop being permanently secured to the waistband at its end farthest from its respective button, with its free end extending toward the said button, and normally held at a suitable predetermined distance therefrom, said loops being adapted to be removably connected with its respective button, said construction providing that the fold in the waist, for each loop, will be at a distance from and on each 85 side of the button.

ALBERT GREENEBAUM.
